UNITED STATES PATENT OFFICE

WILLIAM WATTERS PAGON, OF BALTIMORE, MARYLAND

AIRSHIP

Application filed February 10, 1928, Serial No. 253,437. Renewed March 25, 1932.

One of the objects of the present invention is to provide a novel truss which is applicable to the framework of an airship or to other structures, wherein the stress on each member 5 of the truss can be determined by calculation, irrespective of the lengthening or shortening of the truss members under load, the invention thus enabling a statically determinate truss to be designed and constructed in accordance with the load which it is to carry. The invention provides a truss system which is especially applicable to airships of the types employing buoyant gas cells, the trusses when so employed being capable of 10 being easily designed and constructed to have sufficient strength to withstand the bending or shearing stresses and other loads imposed upon them in structures of this kind without adding unnecessary and undesirable weight thereto, it being made possible to determine 15 the stresses which will be imposed on each truss member and to make each truss member of a cross section in proper proportion to its actual stress. If it is desired in airships designed to warfare or for other reasons one or 20 more superfluous or redundant members may be added so that injury to a member will not impair the navigability of the ship, and yet it will still be possible to determine the actual 25 stresses in all members. Also, in the preferred form of the improved truss as applied to airships embodying gas cells, the diagonal members of the trusses are so arranged 30 that they offer minimum obstruction to the gas cells so that the latter may be made of maximum size and fouling or other interference between the gas cells and the trusses is avoided.

Another object of the invention is to provide a framework for airships which embodies a series of members arranged transversely to its longitudinal axis, these members being spaced longitudinally so that they lie between the series of gas cells, 35 preferably in the planes of the verticals of the trusses, and they support bulk-head wirings so arranged that should a gas cell become punctured and consequently deflated the bulk-head wirings supported by the adjacent transverse members will sustain the

adjacent gas cells against undue longitudinal expansion or displacement.

Another object is to provide nettings for the gas cells and catenaries which span the respective gas cell spaces and are attached at intervals to the gas cell nettings so that they will accumulate the lifting forces applied to the nettings due to the buoyancy of the gas in the gas cells, the catenaries functioning to transfer the lifting forces thus accumulated in them to the transverse members or main framework of the structure, and the catenaries for the different gas cells are connected to one another throughout the length of the structure so that the pull exerted on each catenary will be largely sustained and neutralized by the pull exerted on the catenaries for the adjacent cells.

Another object of the invention is to provide novel and improved cover supports for airships or similar structures and novel means for mounting the cover and its supports on the main framework whereby rupture or other damage to the cover or its supports may occur without causing damage to the main framework. A further object of the invention is to provide tie members at the nose or tail or other part of an airship in conjunction with continuations of the longitudinal of the truss members of the main framework whereby the series of trusses extending longitudinally of the structure are effectually sustained.

To these and other ends, the invention consists in certain improvements and combinations and arrangements of parts all as will be hereinafter more fully described, the features of novelty being pointed out particularly in the claims at the end of the specification.

In the accompanying drawings:—

Figs. 1 and 1^a are collectively a side elevation of an airship embodying the present invention, the cover and other parts thereof being omitted for clearness in illustration;

Fig. 2 represents a transverse section through the airship, taken on the line 2—2 of Fig. 1 and being shown on an enlarged scale;

Fig. 3 represents a partial transverse vertical section on an enlarged scale taken on the line 3—3 of Fig. 1;

Fig. 4 is a fragmentary view on an enlarged scale and in elevation, showing the lower portion of one of the transverse members, the lower portion of one of the trusses associated therewith and the catenaries for one of the gas cell nettings;

Fig. 5 is an elevation of the structure shown in Fig. 4 as viewed from the right in that figure;

10 Fig. 6 is a top plan view of the structure shown in Fig. 5;

Fig. 7 is a diagrammatic view of one panel of an airship employing another form of truss structure which provides eight longitudinals for the ship; and

15 Fig. 8 represents a transverse section taken on the line 8—8 of Fig. 7.

Similar parts are designated by the same reference characters in the different views.

20 The invention is shown in the accompanying drawings and will be hereinafter described in detail as applied to an airship of the type employing a series of longitudinally spaced gas cells for lifting it and for supporting it while in flight, the features of the present invention being especially applicable to such structure, but it is to be understood that the invention, in part or in whole, and especially the trusses may be applied to other structures or other uses and hence it is to be understood that the invention is not restricted to airships. The preferred embodiment of the invention is shown in the accompanying drawings but the invention is not restricted to the precise construction shown as equivalent constructions may be used and such are contemplated within the scope of the claims.

25 The airship shown in the present instance comprises generally a series of longitudinally spaced transverse members 1 which lie in vertical planes or planes perpendicular to the longitudinal axis of the ship and are ring-like in form to conform substantially with the transverse contour of the ship, the spaces 2 between the transverse members serving to accommodate the gas cells which are not shown but may be of the common or well known type, a framework composed of trusses 3 which are arranged in series longitudinally of the ship, and an outer cover 4 which may be of suitably treated fabric such as that usually employed for such purposes, or of metal sheets or other material the cover enveloping the transverse members and the framework and other parts of the ship. The airship is provided with stabilizing fins 5 and rudders 6 which are supported on the stern-post of the ship and may be provided with the usual controls, a control cabin 7 which is preferably located beneath and toward the nose of the ship, and fore and aft propellers 8, 9 and 10 which serve for the propulsion of the ship. A walkway 11 preferably extends longitudinally within the ship

substantially throughout its length and in the plane of the central longitudinal axis of the ship or within the spaces enclosed by trusses 3, for the convenience of the crew in passing from one part to another of the ship, and transverse walkways leading laterally from the longitudinal walkway extend within the bottom, sides and top of the transverse members 1.

70 Each transverse member, according to the present invention is polygonal or approximately circular in form, its diameter being equal substantially to the diameter of the ship at the point in the length thereof at which such frame is placed, the transverse members being reduced in size toward the nose and the tail of the ship to conform with the longitudinal contour or cross section thereof. A suitable number of the trusses 3 are arranged symmetrically around the transverse members, there being in the construction shown in Figs. 1 to 5 inclusive, four trusses at the fore and aft side of each transverse member, the trusses lying in four planes 75 arranged in such relation as to conform approximately with the polygonal outline of the transverse member. The trusses are provided on both of the fore and aft sides of each transverse member, as will be clear from the diagrammatic illustration in Figs. 1 and 1a. The trusses comprise chord or longitudinal members 13 which are fixed at 14 to the respective transverse members and extend from the fore and aft sides thereof, and diagonals 16 which connect the outer ends of these chord or longitudinal members of the circumferential series of trusses. The fore and aft ends of the longitudinal members 13 of the circumferential series of trusses are joined at 15 to the corresponding members 80 of the adjacent circumferential series of trusses spanning the gas cell spaces 2 which lie between them. In order to enable gas cells of maximum size to be accommodated in the spaces 2 without fouling or other interference 85 between the gas cells and the diagonals of the trusses, especially when circumferential series of four trusses are employed, as is shown in Figs. 1 to 5 inclusive, it is preferable 90 to provide the trusses with diagonals each 95 of which is composed of a pair of members 16 and 17 which are arranged in angular relationship so that they converge to the point 18 which is adjacent to the point 14, the proximate ends of these diagonal members 100 being joined at the point 18, the other end of the diagonal member 16 being fixed to the longitudinal member 13 at the point 15 and the other end of the diagonal member 17 being joined at 19 to the corresponding diagonal 105 member of the next adjacent truss in the circumferential series. A secondary diagonal or strut 20 is fixed to the junction point 18 of the diagonal members and to the point 14 110 at which the truss chords or longitudinal 115 members 13 meet. The trusses are connected 120 to the transverse members 1 by means of diagonal members 21 which are arranged in angular 125 relationship to the longitudinal members 13 and 140 the diagonal members 16 and 17, the proximate ends of the diagonal members 21 being joined to the longitudinal members 13 and 14 at the points 15 and 16 respectively, the other ends of the diagonal members 21 being joined to the transverse members 1 at the points 14 and 15 respectively. The longitudinal members 13 and 14 are connected to the transverse members 1 by means of diagonal members 22 which are arranged in angular 130 relationship to the longitudinal members 13 and 14, the proximate ends of the diagonal members 22 being joined to the longitudinal members 13 and 14 at the points 15 and 16 respectively, the other ends of the diagonal members 22 being joined to the transverse members 1 at the points 14 and 15 respectively.

members 13 are fixed to the transverse member.

A truss constructed as shown and described is statically determinate, as the stresses imposed upon its members by bending or shearing forces or other loads imposed upon the structure can be readily and accurately calculated, and in consequence, the cross sections of the truss members can be made proportionate to the actual stresses thereon, thereby insuring ample strength in the truss to sustain loads thereon up to a desired or predetermined limit without adding excess weight, which would be especially undesirable in an airship. While the truss as shown is statically determinate as to all of its members, it is to be understood that superfluous or supplementary members may be added thereto if such are desired, as for example, when the airship is to be employed for military purposes, such superfluous members then serving to prevent collapse of the truss structure in the event a member of the truss is shot away or otherwise disabled, and in such truss structure, it might then not be statically determinate but the additional strength required would be known and the strength of the additional member would be known so that the structure might correctly be described as being statically indeterminate to a predetermined or desired extent.

The actual members composing the trusses may be made in different ways, but inasmuch as the members of the trusses may be called upon to sustain compression stresses as well as tension stresses, according to the direction in which the forces act, rigid members are shown and it is preferable to construct each truss member of one or more tubes or other shapes which, in airship construction are composed preferably of duralumin or other metal or alloy possessing the desired strength coupled with lightness in weight, tubing being particularly suitable because of its resistance to buckling under compression loads. For example, as shown in Figs. 4, 5 and 6, the truss members 17 are composed of a group of four tubes arranged in rectangular relationship, and the group of tubes may be stiffened by a lattice work 21. The group of tubes forming the diagonal members 17 may be continued beyond the point 18 so that they will also form the secondary diagonals 20, as is shown in Fig. 4, and the opposite ends 55 of each of these groups of tubes may be fixed to the respective corners of the transverse member 1 by a gusset plate 22 to which they may be riveted, welded or otherwise suitably secured. The directly opposite truss members 16 at the fore and aft sides of each transverse member are preferably constructed of a group of three tubes or other shapes, as shown in Figs. 4 and 5, and these tubes may extend continuously from the point 15 at one 65 side of the respective transverse member to

the point 15 at the opposite side thereof, the tubes composing the truss members 16 being riveted, welded or otherwise secured to the diagonal truss members 17 at the points 18, as is shown in Fig. 4. The polygonal transverse member 1 is also preferably composed of a group of tubes or other shapes bent at the corners or angles therein to conform with its polygonal outline, and the corners of the tubing composing the transverse member are riveted, welded or otherwise secured to the plates 22 the transverse member being thus secured to the enclosed framework constituted by the trusses. The directly opposite longitudinal members 13 of the trusses at the fore and aft sides of each transverse member are preferably composed of a group of three tubes or other shapes, as is shown in Figs. 4 and 5, these tubes preferably extending continuously across the junction point 14 and being riveted, welded or otherwise secured to the plate 22 or to the corner of the transverse member 1, while the distant ends of the tubes composing the members 13 are secured together at the points 15 as by riveting or welding them and the adjacent ends of the diagonal members 16 to plates 23 or other connectors, each plate 23 serving to connect the truss members 13 and 16 extending from the plane of one transverse member to the adjacent ends of the members 13 and 16 extending from the plane of the next adjacent transverse member.

By arranging the diagonal members 16 and 17 of the trusses in angular relation, as hereinbefore described, the diagonals of the trusses offer minimum obstruction to the spaces 2 which are to contain the gas cells, and hence gas cells of maximum size and capacity may be accommodated in these spaces without danger of snagging chafing or puncturing of the gas cells by coming in contact with the diagonals of the trusses, and furthermore, the arrangement minimizes or avoids pressure of the gas cells against the diagonal members of the trusses so that no buckling tendency is brought about because of the expansion of the gas cells which takes place when the airship ascends from a lower to a higher altitude.

The longitudinal members 13 may be inclined inwardly as shown so that the junction points 15 between these truss members extending from the plane of one transverse member and the corresponding truss members extending from the plane of the adjacent transverse member will lie within the adjacent corner of the truss system and on the diagonals thereof, as is shown in Fig. 5. Such inward inclination of these truss members has the advantage that it divides the longitudinal forces between each longitudinal member 13 and the pair of diagonal members 16 at the respective corner of the transverse member.

The longitudinal members 13 of the series of trusses are joined end to end at the points 15 and they form in effect continuous main longitudinals lengthwise of the ship, there being four of these longitudinals thus formed in the construction shown in Figs. 1 to 5 inclusive. In order to sustain the series of trusses and transverse members in proper position, tie members 24 are attached to the longitudinals at any suitable point or points on the length of the ship, they being shown for example attached to the points 15 of the foremost trusses, and when these tie members are so applied, they may be connected at the point 25 to one another and to a nose spindle 26 which may be provided with a mooring cone or other attachment for connecting it to a mooring mast. Longitudinal truss members 13^a may be extended rearwardly from the rearmost trusses of the framework and anchored at the apex of the tail of the ship. Diagonals 27 and cross members 28 are preferably arranged between the extended longitudinal members 13^a to stabilize the truss system composing the framework and to stiffen and strengthen the tail supporting members 13^a.

Each transverse member 1 contains a bulk-head wiring 29 which is composed preferably of a number of wires or of a single wire arranged in a form similar to that of a spider web, these wires or the convolutions thereof being arranged one within the other around or substantially concentrically of the longitudinal axis of the structure, and these wires are supported by diagonal wires 30 which extend diagonally between the corners of the respective transverse member and are tied thereto and to the framework. The wires 29 composing the bulk-head are preferably made just taut or with a predetermined excess length rather than placed under initial tension, so that they will bulge under the pressure of the gas in a gas cell at either side thereof without imposing excessive ring compression on the respective transverse member 1. These bulk-head wirings which are arranged within the different transverse members lie between the gas cells contained in the spaces 2 and they prevent surging of the gas cells in a direction axially, of the ship, and in the event of deflation of any of the gas cells due to puncture thereof or other causes, the bulkhead wirings at opposite sides of the deflated gas cell will sustain the pressure of the gas in the adjacent gas cells, displacement of or injury to the adjacent gas cells being thereby avoided. If desired, the mid-points of the diagonal wires 30 may be secured to an axial cable 100 which may be secured in the usual way at the nose and tail of the ship, the axial cable then assisting the bulk-heads in sustaining the displacing tendency of the gas cells.

The gas cells are confined by gas cell net-

tings 31 which encircle the respective cells, and the lifting forces applied to these nettings by the gas cells are sustained by catenaries 32 which are fixed to the lower corners of the respective transverse members and the enclosed framework, as at 33 so that these catenaries loosely span the gas cell spaces. The catenaries are attached to the gas cell nettings by wires 34 which are attached to the nettings at suitably distributed points whereby each catenary will accumulate the lifting force imposed upon each netting by the respective gas cell, the catenaries transmitting such lifting forces to the main framework of the structure. The sag of the catenaries will preferably equalize or partially equalize the longitudinal pressure exerted on the bulk-head wirings, and the longitudinal pull of adjacent catenaries will neutralize each other, and as these catenaries are arranged end to end, there will be only slight, if any, longitudinal forces applied to the frame structure at the points where these catenaries are attached. Furthermore, the sag of these catenaries is preferably so adjusted that if a gas cell becomes deflated, the longitudinal pressure of the adjacent cells on the bulk-head wirings at opposite sides of the deflated cell will largely neutralize the pull of the catenaries in the adjacent cell spaces, and hence the stability of the structure in such an event will be preserved. Supplementary catenaries 35 are also preferably provided for supporting a gas cell in the event of its deflation, these catenaries being fixed to the transverse members and the enclosed framework at the points 36' so that they will bridge the respective gas cell spaces and support the gas cell if deflated.

The outer cover 4, which may be of metal or any suitably treated fabric or material such as that generally used for such purposes, is supported by an appropriate number of longitudinal cover supports 36 over which the outer cover is laid. These cover supports are preferably composed of tubing or other shapes extending longitudinally of the ship and being spaced at suitable intervals in a circumferential direction. Each cover support is preferably of catenary construction, the tubular member 36 having struts 37 secured thereto to project inwardly therefrom, these struts being relatively short near the planes of the transverse members but increasing in length as they approach the middle of the span between transverse members, and a tensioned wire or wires 38 extends longitudinally at the inner side of the member 36 and bears on the inner ends of the struts, the construction as just described providing a cover support which will effectually resist forces tending to deflect the cover inwardly. A similar inverted wire or wires 39 may be inserted and connected to the struts to provide

means for resisting any outward forces that may come to act on the struts 37.

The cover supports are secured to the series of longitudinally spaced circumferentially extending transverse members 1, each of these transverse members comprising preferably a group of three tubes or other shapes arranged in triangular relation, the outermost tube, in the construction shown, being preferably arranged at the apex of the triangle and secured to the longitudinal cover supports 36 by sleeves 40 or other suitable means, the tubes comprising these circumferential supports being maintained in triangular relationship by the lattice 21 and tie plates 41, one of these tie plates being preferably applied to the circumferential support at each point where it joins a longitudinal cover support.

Each transverse member 1 is secured to the portion of the main framework which it encircles by a system of struts 42, each strut being composed preferably of a set of three tubes or other shapes which may be riveted, welded or otherwise secured at their inner ends to the tubing composing the truss members 17 of the framework and at their outer ends to the respective tubes composing the circumferential transverse member. These struts are adapted to sustain compression stresses between the respective transverse members and the main framework, and in order to sustain tension stresses between these parts, a system of stay wires or rigid struts 43 composed of steel or other metal is arranged between the tie plates 41 of the circumferential transverse members and the respective pairs of truss members of the framework. By locating the circumferential transverse members in the median planes of the respective pairs of truss members, the struts 42 and stay wires 43 will have a divergent form as will be clear from Fig. 6, and this divergent arrangement of the struts and tie wires will effectually prevent upsetting of the circumferential transverse member or movement thereof longitudinally with respect to the framework.

Knee members, composed preferably of groups of tubing or other shapes 44 are preferably extended diagonally across certain corners of the respective transverse members and riveted, welded or otherwise fixed thereto at their ends and to the truss or frame members 17 at intermediate points, these knee members serving to reinforce and strengthen and stiffen the sides of the ship, and also to resist wind pressure when the ship is held on or close to the ground. The transverse members lying in the planes of the sections 2-2 and 3-3 of Fig. 1 are formed with depressions 45 and 46 respectively to provide engine compartments within the ship to contain the engines 47 and 48 which drive the propellers 8 and 9 respectively, and the knees 44 serve to reinforce the portions of the ship which form

the engine rooms and thus enable these portions of the ship to sustain the weight of the engines. While the engines employed to drive the propellers are arranged within the hull of the ship where they will be conveniently accessible for adjustment and repair, the engines are connected to drive the propellers which are located exteriorly of the hull, by shafts 49 and 50 which may be connected to the respective propeller shafts by suitable gearing. However, the depressions 45 and 46 may be omitted and the engines and other apparatus placed in separate cars suspended from the transverse and longitudinal members.

Instead of a truss structure which provides four longitudinals, such for example as that hereinbefore described other truss structures providing a greater number of longitudinals may be employed; and an example of such a structure is shown diagrammatically in Figs. 7 and 8. In this embodiment of the invention, Fig. 7 represents a side elevation of one of the amidship gas cell panels, the circumferential trusses at the fore and aft ends thereof being shown. 1^a represents the two adjacent transverse members of the ship which may support the outer cover substantially in the manner hereinbefore described, or may be located at the inner apex of the transverse frame and 2^a designates the gas cell space formed between them. The truss structure forming the framework, in this embodiment, comprises truss verticals composed of rigid members 51 and 52 which are preferably stiffened by lattice-work 53, these members extending in the direction of the transverse circumference of the ship within the diameters of the respective transverse members and they may be joined and secured thereto by a system of struts or stay wires, or both, similar to that hereinbefore described for the transverse members 1. In this instance, eight trusses compose each circumferential series, there being a set of eight truss chords or longitudinal members 54 proceeding fore and aft from the truss verticals 51 and 52 and eight pairs of truss diagonals 55. The truss chords or longitudinal members 54 of the longitudinally adjacent series of trusses as shown are in alinement and are joined at their ends 56 and the distant ends of the circumferentially adjacent truss diagonals 55 are joined at these same points, the alined chords of the trusses forming longitudinals which are continuous throughout the length of the ship and the truss diagonals being joined thereto at the mid-points between adjacent truss verticals. The other ends of the truss diagonals are joined to the respective truss verticals 51 and 52 at the mid-points in the circumferential lengths thereof between the longitudinals. In such a truss structure, the diagonals 55 and chords 54 of the circumferential series of trusses 130

will lie substantially in the planes of the sides of an octagon and hence the truss diagonals will not extend into the gas cell space sufficiently to interfere appreciably with the 5 gas cell therein, and moreover, the gas cell space may be of increased size for a ship of given transverse diameter, as compared with truss structures which form a smaller number of longitudinals.

19 In both embodiments of the invention herein shown, the longitudinal cover-supporting members are effectually supported by the transverse members which are spaced at suitable intervals longitudinally of the ship and are capable of sustaining the stresses which act on the cover, and the ship is enabled to sustain bending and shearing stresses imposed thereon by the interior framework which is contained within and secured to the 25 transverse members but is not subject to injury in case the outside cover or its supports are injured. The truss structures composing the framework afford great strength and rigidity in relation to the weight thereof, 30 and by employing trusses which are statically determinate, the stresses acting on the different members of the trusses can be calculated so that the truss members may be constructed of suitable cross sections to sustain the actual stresses that may be imposed 35 thereon. While it will ordinarily be sufficient to construct each truss of sufficient members to render the truss statically determinate, it may be desirable in some cases, as for 40 example, where the ship is to be employed for military purposes, to add to the trusses superfluous or auxiliary members which will prevent collapse of a truss in the event one of its primary members is shot away or otherwise injured.

I claim as my invention:—

1. An airship structure comprising longitudinally spaced members providing gas cell spaces between them, a gas cell netting in each space, and a pair of catenaries spanning each space and having their ends connected to the adjacent members to sustain respective the lift of a buoyant cell and the weight of the cell when deflated, the lift sustaining 50 catenary having connections between its intermediate portions and the netting.

2. An airship structure comprising longitudinally spaced members providing gas cell spaces between them, a gas cell netting in each space, a transverse bulkhead within and connected to each member dividing adjacent gas cell spaces, and catenaries spanning the spaces and connected at their ends to the respective members, the intermediate portions 55 of the catenaries being connected to the respective gas cell nettings whereby the longitudinal tension exerted on said members by a catenary will oppose the opposite longitudinal force exerted on the adjacent bulkheads.

3. A cover support for airships and the like comprising a cover-supporting member, struts extending transversely from one side thereof, and reversely curved wires extending longitudinally of said member at one side thereof and cooperative with said struts to resist bending of said member in either of two opposite directions.

4. In an airship, a self contained rigid structure comprising trusswork forming the main framework of the airship, auxiliary framework comprising ring members surrounding said framework at intervals and longitudinals disposed in spaced relation therearound and extending to adjacent ring members, said auxiliary framework being of comparatively light materials, said self contained rigid structure being adapted to sustain all major loading on said airship.

5. In an airship, a self contained rigid framework comprising a series of longitudinally connected girders arranged in order about an axis, transverse braces connecting said girders to form a rigid structure, ring members surrounding said framework and attached to said transverse braces, each of said ring members together with the braces adjacent thereto constituting a main transverse ring for the airship, and cover supporting means surrounding said rings and said framework and sustaining the lift of the gas carried by said ship.

6. In an airship, main transverses, circular and longitudinal cover supporting means supported by said transverses, and longitudinally extending rigid trusswork within the framework defined by said cover supporting means connecting said transverses, said transverses and said trusswork comprising a self contained structure adapted to sustain 105 all major loading on said airship.

7. In a rigid airship, transverse cover supporting rings, longitudinal girders connected to said rings in spaced relation around the periphery thereof, main transverse rings interiorly of said cover supporting rings and trusswork extending from each ring to each of said main rings adjacent main ring interiorly of said longitudinal girders, said main rings and said trusswork being rigidly attached together to form a framework for said airship statically determinate as to all stresses therein.

8. In a rigid airship, a primary framework to sustain major loading and a secondary framework supplemental to said primary framework, said primary framework comprising transverse rings and trusswork between said rings, said secondary framework comprising outer cover supporting ring members and longitudinal girders rigidly supported by said transverse rings in spaced relation around the periphery thereof to support the cover of said ship in conjunction with said outer ring members, said primary 125 130

trusswork being disposed internally of said secondary framework, said trusswork and said transverse rings comprising a statically determinate framework for said airship.

9. In a rigid airship, transverse cover supporting rings and longitudinal ties attached to said rings in spaced relation around the periphery thereof, said ties defining the outward contour of said ship and comprising a cover support therefor, internal ties for each of said rings spanning arcs thereof in forming closed geometrical figures, the figures in one ring being geometrically equivalent to the figures defined by the ties in adjacent rings, each of said figures comprising main transverse rings, and trusswork connecting corresponding sides of adjacent figures, said cover supporting transverse rings, said ties and said trusswork comprising a framework for said airship wherein all stresses are statically determinate.

10. In a rigid airship, transverse rings having internal trusswork in the plane of said rings comprising beams spanning arcs around the circumference thereof to form closed geometric figures, auxiliary trusswork for said rings out of the plane of said rings but rigidly attached thereto, trussing connecting the auxiliary trusswork of each ring with each adjacent ring to form a framework for said airship statically determinate as to all stresses therein.

11. In a rigid airship, transverse rings having internal trusswork in the plane of said rings comprising beams spanning arcs around the circumference thereof to form closed geometric figures, auxiliary trusswork for said rings out of the plane of said rings but rigidly attached thereto, the outer ends of said auxiliary trusswork converging towards the ends of said beams to terminate in the plane of its ring, and trussing connecting the auxiliary trusswork of each ring with the supplemental trusswork of each adjacent ring to form a framework for said airship.

12. In a rigid airship, transverse rings having internal trusswork in the plane of said rings comprising beams spanning arcs around the circumference thereof to form closed geometric figures, auxiliary trusswork for said rings out of the plane of said rings comprising beams on either side of oppositely disposed beams in said rings, each of said beams and the auxiliary trusswork therefor lying substantially in the same plane, said plane being substantially parallel to the axis of said airship, trussing connecting the auxiliary trusswork of each ring with similar auxiliary trusswork of adjacent rings to form a rigid framework for said airship.

13. In a rigid airship, transverse rings having internal trusswork comprising beams spanning arcs around the circumference thereof to form closed geometric figures, auxiliary trusswork for each of said beams lying

in a single plane, said plane being substantially parallel to the axis of said airship, and longitudinal girders extending past each ring throughout the entire length of the airship, said girders being rigidly attached to said auxiliary trusswork of each ring to form a continuous integral framework statically determinate as to all stresses.

14. In a rigid airship, transverse rings having internal trusswork comprising beams spanning arcs around the circumference thereof to form closed geometric figures, auxiliary trusswork for said rings out of the plane of said rings but rigidly attached thereto, the outer ends of said auxiliary trusswork converging towards the ends of said beams to terminate in the plane of its ring, trussing connecting the supplemental trusswork of each ring with the supplemental trusswork of each adjacent ring, said trusswork comprising double girders, one of said girders being attached to the point of convergence of said beams and said trusswork at a point substantially adjacent the periphery of said rings, the other of said girders being attached to said trusswork at a point substantially interior of said airship, said girders both extending to an adjacent ring for rigid attachment thereto to form a rigid framework for said airship.

15. In a rigid airship, transverse rings having internal trusswork comprising beams spanning arcs around the circumference thereof to form closed geometric figures, auxiliary trusswork for said rings out of the plane of said rings but rigidly attached thereto, the outer ends of said auxiliary trusswork converging towards the ends of said beams to terminate in the plane of its ring, trussing connecting the supplemental trusswork of each ring with the supplemental trusswork of each adjacent ring, said trusswork comprising double girders, one of said girders being attached to the point of convergence of said beams and said trusswork at a point substantially adjacent the periphery of said rings, the other of said girders being attached to said trusswork at a point substantially interior of said airship, said girders each extending diagonally to an adjacent ring whereby said first mentioned girder is attached to a point on said adjacent ring corresponding to the point of origin of the second named girder from said first named ring and said second named girder extending outwardly for attachment to said adjacent ring at a point adjacent the periphery thereof.

16. The combination as set forth in claim 15 wherein said diagonally disposed double trusswork is continuous throughout the entire length of the framework of said airship.

17. In a rigid airship, transverse rings having internal trusswork comprising beams spanning arcs around the circumference thereof to form closed geometric figures, aux-

- iliary trusswork for said rings out of the plane of said rings but rigidly attached thereto, said auxiliary trusswork comprising means disposed on either side of said ring, 5 said first named beams and said auxiliary trusswork lying in a plane substantially parallel to the axis of the airship, the auxiliary beams approaching nearest said first named beams at a point substantially midway of the ends thereof and gradually diverging therefrom to a desired point, said auxiliary beams converging from said desired point to terminate in the plane of said first named beams, and double trusswork connecting adjacent 15 rings, said double trusswork originating at the point of convergence of said beams, and from the point of greatest divergence of said auxiliary beams and extending to an adjacent ring for rigid attachment thereto.
18. In a rigid airship, transverse rings having internal trusswork on either side of the plane of said rings comprising beams spanning arcs around the circumference thereof to form closed geometric figures, auxiliary trusswork for said rings out of the plane of said rings but rigidly attached thereto, said auxiliary trusswork comprising beams slightly diverging from a central point away from said first named beams to a desired point and diverging towards said first named beams to terminate substantially in the plane of said rings, and double trusswork extending throughout the length of said ship for alternate attachment to said 30 rings at the points of convergence of the beams and to maximum points of divergence of the beams comprising the auxiliary trusswork.
19. The combination as set forth in claim 18 wherein the double trusswork is composed of rigid diagonals having their points of crossing substantially midway between adjacent rings, said diagonals being rigidly attached to each other.
20. In a rigid airship, transverse cover supporting rings, longitudinal girders disposed in spaced relation around the periphery of said rings and rigidly attached thereto, beams spanning adjacent arcs of said 35 rings to form main transverse rings, and diagonally extending trusswork disposed in spaced pairs within said longitudinals bracing said main transverse rings with respect to each other and each adjacent ring whereby a self contained braced framework is provided for said airship.
21. In a rigid airship, transverse rings, longitudinal girders disposed in spaced relation around the periphery of said rings and rigidly attached thereto and diagonally extending double K trusswork interiorly of the structure defined by said longitudinals connecting and bracing adjacent rings, said 40 diagonals crossing at a point substantially midway of their length, and plates rigidly

attached to both of said diagonals to form a rigid and durable trusswork.

22. A transverse ring for airships comprising three sets of girders comprising polygons, two of said polygons being of equal perimeter, the other of said polygons having a greater perimeter, all of said polygons being in different planes, the first two of said polygons being designed to withstand a greater amount of loading than the larger 75 of said polygons and being attached to said larger polygon.

23. In a transverse ring for airships, two concentric polygons composed of girders, one of said polygons comprising the outer member and defining the periphery of said ring, the other of said polygons comprising the inner member and having a fewer number of sides than said outer member, said inner member having greater inherent strength 80 than said outer member, and trusswork connecting said members in rigid relation at frequent intervals around the peripheries thereof.

24. In a transverse ring for airships, an outer polygonal structure and an inner polygonal structure having its vertices rigidly attached to said outer structure, diagonals connecting opposite vertices of said inner polygon and a nest of graduated polygons 95 geometrically equivalent to said inner polygon attached to said diagonals and forming a bulkhead for gas cells.

25. In a transverse ring for airships, an outer polygonal member, an inner polygonal member having its vertices rigidly attached to said outer member, and trusses extending from one point on said outer polygonal member to another point thereof, said trusses and the arc of the outer member spanned thereby 100 enclosing a vertex of said polygonal member and being rigidly attached to said outer polygonal member to strengthen the connection and distribute the loading on said vertex.

26. In a transverse ring for airships, an outer polygonal member, an inner polygonal member having its vertices rigidly attached to said outer member, and trusses extending from points on said outer member below each of said vertices whereby said trusses and the arcs of the outer member spanned thereby 115 each include a vertex of said inner polygon, said trusses each being rigidly attached to said inner polygon at the points of crossing.

27. The combination as set forth in claim 26 wherein said trusses continue around the perimeter of said ring to form rigid connection between said outer member and said inner polygon at a plurality of points 125 around the perimeter thereof.

28. In a transverse ring for rigid airships, an outer polygonal member, an inner quadrilateral each component side thereof having greater inherent strength than any com- 130

ponent side of said polygonal member disposed within said polygonal member and having the vertices thereof rigidly attached directly to said outer member, trusswork connecting the sides of said quadrilateral and said outer member at frequent intervals around said ring, said trusswork cutting across one vertex of said quadrilateral and being attached thereto at the points of crossing, and diagonals connecting opposite vertices of said quadrilaterals, the entire ring comprising a structure statically determinate as to all stresses therein.

29. The combination as set forth in claim

15 28 together with additional trusswork rendering said ring statically indeterminate to a desired extent.

30. The combination as set forth in claim 28 together with additional trusswork rendering said ring statically indeterminate, 20 said additional trusswork comprising, if desired, trusswork cutting across additional vertices.

31. In a transverse ring for rigid airships, 25 an outer polygonal member, an inner quadrilateral of greater inherent strength than said outer member disposed within said outer member and having the vertices thereof rigidly attached thereto, trusswork connecting the sides of said quadrilateral and said outer member at frequent intervals around the perimeters thereof, certain members of said trusswork cutting across the vertices of said quadrilateral and being attached thereto at 30 the points of crossing, a structural member bisecting the angle of each enclosed vertex, bracing for said structural member comprising girders attached thereto and to the sides of said quadrilateral and diagonals for said 35 quadrilateral attached endwise to said structural member and adapted to sustain and partially comprise a bulkhead between gas cells whereby said entire ring is statically determinate as to all stresses therein.

45 32. In a rigid airship, transverse rings, a main framework comprising beams spanning arcs of said rings and rigid longitudinals connecting said beams to beams in adjacent rings, a secondary framework comprising the 50 arcs of the rings spanned by said beams together with cover supporting means, gas cells enclosed by said cover supporting means, said cover supporting means being adapted to sustain the lift of the gas in said cells and means 55 for transferring the load due to said lift from said cover supporting means radially to said transverse rings.

33. In a rigid airship, transverse rings having internal bracing including beams spanning arcs thereof to form a closed geometric 60 figure, a cover and cover supporting means extending over said rings, and a main framework including diagonals extending from said beams to beams in adjacent rings, said 65 cover supporting means being adapted to

sustain the lift of the gas in said airship for transference to said main framework.

34. In a rigid airship, transverse rings having internal bracing including beams spanning arcs thereof to form a closed geometric 70 figure, a cover and cover supporting means extending over said rings, and a main framework including diagonals extending from said beams to beams in adjacent rings, said cover supporting means being adapted to sustain the lift of the gas in said airship, and means for transferring said lift to said main frame.

35. In a rigid airship, transverse rings having internal bracing including beams spanning arcs thereof to form a closed geometric figure, a cover and a cover supporting means extending over said rings, and a main framework comprising said beams and diagonals 85 extending between rings and connecting corresponding beams of adjacent figures, said cover supporting means sustaining the lift of the gas in said ship and catenaries extending between said rings and tied to said cover supporting means to transfer the loading 90 thereon to said main framework.

36. In a rigid airship, transverse rings, longitudinal structural means connecting said transverse rings and enclosing gas cells, trusswork disposed interiorly of said structural means for maintaining said rings in spaced relation, a netting interiorly of said longitudinal means and exteriorly of said trusswork and catenaries attached to said netting and to said trusswork to distribute the lift of the gas in said cells to predetermined 95 points on said trusswork.

37. In a rigid airship, transverse rings, a netting extending over said rings to confine the gas cells of said airship, rigid trussing connecting adjacent rings and catenaries attached to said trussing and to said netting at a plurality of points between each pair of 100 rings to transfer the lift of the gas in said cells directly to said trussing.

38. In a rigid airship, transverse rings, light longitudinals connecting said rings and enclosing gas cells, a heavy rigid strengthening trusswork within said longitudinals connecting each ring with each adjacent ring, a netting between said longitudinals and said trusswork to take the lift exerted by the gas in said gas cells and catenaries attached to said netting and to said trusswork, said rings, 115 longitudinals, trusswork and catenaries comprising a structure statically determinate as to all stresses in said airship.

39. In a rigid airship, transverse rings, light longitudinals connecting said rings and enclosing gas cells, a heavy rigid strengthening trusswork within said longitudinals connecting each ring with each adjacent ring, a netting between said longitudinals and said trusswork to take the lift exerted by the gas 120 125 130

in said cells and catenaries attached to said netting and to said trusswork, said rings, longitudinals, trusswork and catenaries comprising a structure statically determinate as to all stresses in said airship and additional trusswork attached to said heavy trusswork rendering said structure indeterminate as to stresses to a predetermined degree.

40. In a rigid airship, transverse rings, longitudinal girders attached to said rings, a netting interiorly of said girders enclosing gas cells, catenaries attached to said rings and to said netting and adapted to transfer the lift from the gas in said cells to said rings, and auxiliary catenaries likewise attached to said rings to support a deflated gas cell.

41. In a rigid airship, transverse rings, light longitudinals connecting said rings, a netting interiorly of said longitudinals enclosing gas cells, a heavy rigid strengthening trusswork within said longitudinals connecting each ring with each adjacent ring, catenaries attached to said netting and to said transverse rings to transfer the lift of the gas in said cells to predetermined points, and auxiliary catenaries attached to said rings to sustain said gas cells when deflated.

42. In a rigid airship, transverse rings having internal trusswork in the plane of said rings comprising beams spanning arcs around the circumference thereof to form closed geometric figures, auxiliary trusswork for said rings out of the plane of said rings but rigidly attached thereto, the outer ends of said auxiliary trusswork converging towards the ends of said beams to terminate in the plane of its ring, trussing connecting the supplemental trusswork of each ring with the supplemental trusswork of each adjacent ring to form a framework for said airship, and catenaries attached to each ring at the point of termination of said trusswork with said beams and to a netting enclosing the gas cells of said airship to form an airship statically determinate as to all stresses therein.

43. In a rigid airship, a primary framework to sustain major loading and a secondary framework supplemental to said primary framework, said primary framework comprising transverse rings and trusswork between said rings, said secondary framework comprising longitudinal girders rigidly fixed to said transverse rings in spaced relation around the periphery thereof to support the cover of said ship, said primary trusswork being disposed internally of said secondary framework, said trusswork and said transverse rings comprising a statically determinate framework for said airship, and stabilizing fins rigidly attached to said primary framework whereby the loading on the airship due to said fins is likewise statically determinate.

44. In a rigid airship, a primary framework to sustain major loading and a sec-

ondary framework supplemental to said primary framework, said primary framework comprising transverse rings and trusswork between said rings, said secondary framework comprising longitudinal girders rigidly fixed to said transverse rings in spaced relation around the periphery thereof to support the cover of said ship, said primary trusswork being disposed internally of said secondary framework, said trusswork and said transverse rings comprising a statically determinate framework for said airship, stabilizing fins rigidly attached to said primary framework whereby loading thereon due to said fins is likewise determinate as to all stresses and auxiliary trusswork in said framework to render said framework statically indeterminate.

45. In a rigid airship, a primary framework to sustain major loading and a secondary framework supplemental to said primary framework, said primary framework comprising transverse rings in spaced relation around the periphery thereof to support the cover of said ship, said primary trusswork being disposed internally of said secondary framework, said trusswork and said transverse rings comprising a statically determinate framework for said airship, stabilizing fins rigidly attached to said primary framework to render loading thereon due to said fins likewise statically determinate and additional bracing for said fins rendering the loading on said framework due to the fins statically indeterminate.

46. In an airship, a self contained rigid structure comprising trusswork forming the main framework of the airship, auxiliary framework comprising ring members joined by light longitudinals surrounding said framework at intervals and a network extending over the interior of said rings, said auxiliary framework being of comparatively light materials, said self contained rigid structure being adapted to sustain all major loading on said airship and a corridor extending longitudinally of said airship supported by said main trusswork.

47. In combination in an airship, transverse rings, longitudinal trusses connecting said rings, a corridor extending internally and transversely of said rings, a second corridor extending longitudinally of the airship intersecting the transverse corridors in said rings, said rings comprising an outer circular member and a quadrilateral member within said circular member and having each of its vertices rigidly attached thereto, and structural ties connecting said circular member and said quadrilateral member at frequent intervals therearound, said longitudinal corridor being supported by said structural ties intermediate to vertices of said quadrilateral whereby the loading due to said corridor is

sustained by said rings and distributed thereover in predetermined relation.

48. In a rigid airship, transverse rings, longitudinally extending cover supporting means attached to said rings around the periphery thereof in spaced relation, a main trusswork enclosed by said cover supporting means for maintaining said rings in spaced braced relation, said trusswork comprising polygonal members having each vertex thereof attached to an outer substantially circular ring and rigid trussing connecting each side of each polygon with a corresponding side of a polygon in an adjacent ring, trussing between said outer rings and each of said polygons at frequent intervals therearound, and power plants to drive said airship, said power plants being disposed across the plane of said rings and supported by said trussing whereby the loading due to said plants is distributed to said rings and said trusswork in a predetermined statically determinate relation.

49. In a rigid airship, transverse rings, longitudinally extending cover supporting means attached to said rings around the periphery thereof in spaced relation, a main trusswork enclosed by said cover supporting means for maintaining said rings in spaced braced relation, said trusswork comprising polygonal members having each vertex attached to an outer substantially circular ring and rigid trussing connecting each side of each polygon with a corresponding side of a polygon in an adjacent ring, trussing between said outer rings and each of said polygons at frequent intervals therearound, a corridor extending longitudinally of said ship supported by said trusswork in a predetermined relation with said trusswork, and power plants likewise supported by said trusswork in predetermined relation with said trusswork whereby the entire airship is statically determinate as to all stresses therein.

50. In a rigid airship, transverse rings, longitudinally extending cover supporting means attached to said rings around the periphery thereof in spaced relation, a main trusswork enclosed by said cover supporting means for maintaining said rings in spaced braced relation, said trusswork comprising polygonal members having each vertex thereof attached to an outer substantially circular ring and rigid trussing connecting each side of each polygon with a corresponding side of a polygon in an adjacent ring, trussing between said outer rings and each of said polygons at frequent intervals therearound, and power plants to drive said airship, said power plants being disposed across the plane of said rings and supported by said trussing whereby the loading due to said plants is distributed to said rings and said trusswork in a predetermined statically determinate relation, and auxiliary trusswork for supporting said power plants whereby the loading due

thereto is rendered statically indeterminate.

51. The combination as set forth in claim 47 together with auxiliary trusswork disposed across vertices of said polygonal members to provide additional support thereby rendering the framework of the airship statically indeterminate to a predetermined extent.

52. In a rigid airship, transverse rings and longitudinal girders connecting said rings, catenaries attached to each of said girders and extending between said rings to assist said girders to resist outward deformation thereof due to pressure of the lifting gas thereagainst and structural wires for bracing said girders and catenaries against torsion.

53. In a rigid airship, transverse rings and longitudinal girders connecting said rings, catenaries attached to each of said girders and extending between said rings to assist said girders to resist inward deformation thereof due to pressure against the cover of said airship, and structural wires for bracing said girders and catenaries against torsion.

54. In a rigid airship, a main framework including transverse rings, longitudinal girders disposed around the periphery of said rings to support the cover of the airship, and opposed catenaries carried by said girders, one of said catenaries resisting inward deformation, the other of said catenaries resisting outward deformation.

55. In a rigid airship, a main framework comprising transverse rings and longitudinally disposed trusswork connecting said rings, rigid cover supporting means supported in spaced relation around said rings around the periphery thereof exteriorly of said trusswork, a catenary carried by said means and rigid ties connecting said means to said main framework whereby said means and said catenaries are maintained in substantial radial alignment with respect to said airship.

56. In a rigid airship, transverse rings and longitudinal girders connecting said rings, catenaries attached to each of said girders and to each of said transverse rings to resist deformation of said girders, graduated rigid struts between said girders and said catenaries and diagonal structural means for bracing said girders, said struts and said catenaries against torsion.

57. In a rigid airship, transverse rings and longitudinal girders connecting said rings, catenaries attached to each of said girders and to said rings to assist said girders in resisting inward and outward deformation, graduated rigid struts attached to said girders for maintaining said catenaries in the most advantageous position therewith, means for bracing said girders and catenaries against torsion, and wire mesh comprising gas cell containers interiorly of said girders

and attached to said struts for assuming the lift of the lifting gas.

58. In a rigid airship, transverse rings, longitudinal members connecting said rings and maintaining said rings in spaced braced relation, a netting interiorly of said ring and said longitudinal members, gas cells enclosed by said longitudinal members, and catenaries attached to said ring and to said netting,
5 said catenaries transferring the lift of said gas on said netting radially to said rings.

20 In testimony whereof I have hereunto set my hand.

WILLIAM WATTERS PAGON.
